UNITED STATES PATENT OFFICE.

CHARLES ROBERT WOOD, OF MEMPHIS, TENNESSEE, ASSIGNOR OF ONE-FOURTH TO
W. E. MOSS AND ONE-FOURTH TO B. C. GOODRICH, BOTH OF MEMPHIS, TENNESSEE.

COTTON CLEANER AND BOLL CRUSHER.

Application filed April 6, 1921. Serial No. 459,034.

To all whom it may concern:

Be it known that I, CHARLES ROBERT Wood, a citizen of the United States of America, residing at Memphis, in the county 5 of Shelby and State of Tennessee, have invented certain new and useful Improvements in Cotton Cleaners and Boll Crushers, of which the following is a specification.

This invention relates to cotton cleaners 10 and it consists in the novel features herein-after described and claimed.

An object of the invention is to provide a cotton cleaner of simple and durable structure adapted to be applied to the intake pipe 15 of a pneumatic cotton conveyer system and which serves to break the twigs, leaves and hulls without too finely dividing them and which effects ultimate loosening and separation of the said broken material together 20 with a good deal of the sand and grit, stone, metal and other foreign matter from the cotton, so that during the ginning operation these foreign substances broken hulls, leaves 25 and other trash will be eliminated from the ginned cotton.

A further object of the invention is to provide in a cotton cleaner of the character stated means for partially compressing the bolls of cotton, causing their hulls to open 30 as nature has provided, so that the strands of the cotton fibre are bunched together and are not broken or injured during the cleaning and separation as stated, but subjected to successive rolling and crushing actions during 35 their advancement within the cleaner without breaking the hulls and other material into minute particles, and therefore preventing the cotton passing to the gin being filled with fine matter that cannot be 40 readily separated therefrom and which lowers the value of the ginned cotton.

With these and other objects in view, as will appear as the description of the apparatus progresses, the cleaner comprises a 45 casing which is connected with the horizontal run of the cotton intake pipe of the cotton conveying system.

The casing is provided at its lower portion with a hopper adapted to receive the 50 trash. The casing is provided at one side with a duct through which the current of air and the uncleared cotton are introduced into the casing. The said duct is located between the upper and lower ends of the casing.

The casing is provided at its top and at 55 that side opposite the side at which the first-mentioned duct is located with a second duct through which the partly cleaned and crushed cotton passes out of the casing.

A screen or foraminous drum is journaled 60 for rotation in the casing and is disposed between the said ducts and above the hopper. A hood is mounted upon the top of the casing and communicates with the same. A breaker is journaled for rotation in the 65 hood on an axis parallel with the axis of the drum and the breaker is provided at its periphery with a series of ridges with intervening furrows and outstanding pins are mounted upon the peaks of the ridges to 70 loosen the cotton on the screen and to assist the suction draft in removing the cotton from the screen.

In the accompanying drawings:—

Figure 1 is a longitudinal sectional view 75 of the cotton cleaner.

Figure 2 is a transverse sectional view of the same cut on the line 2—2 of Figure 1.

Figure 3 is a fragmentary side elevation of the cotton cleaner. 80

Figure 4 is an enlarged sectional view of the breaker of the cotton cleaner.

As illustrated in the accompanying drawing the intake pipe of the seed cotton pneumatic conveying system is shown at 1 and 85 the said pipe communicates at its upper end with a horizontal run 2 in a usual manner and the said run communicates with a depressed by-pass pipe 3. A valve mechanism 4 is connected with the outlet end of the by-pass pipe 3, for delivery of the cotton to a feed hopper 4^a shown in association with a conveyor 4^b to receive overflow cotton from the hopper, which valve and its associated elements are the subject-matter of an application filed May 13, 1919, Serial No. 296,851, 90 and are fully described and claimed therein.

The valve 4 comprises a cylinder disposed in the suction line and mounted to oscillate to alternately establish and cut off the suction draft therethrough, and at each oscillation cutting off the suction, to deposit the cotton collected on a screen therein. The discharge of the cotton being through the same opening that receives the cotton when 100 the suction is established by the return oscillation.

The cotton cleaner comprises a duct 5

which is located above and upon the by-pass pipe 3. One end of the duct 5 normally communicates with the interior of the horizontal run 2 of the pipe 1 and the intake end of the by-pass pipe 3 is normally closed by a valve 6 which is hingedly mounted at the lower edge of the duct 5 and at the intake end thereof and which may be swung from a position over the adjacent end of the by-pass pipe to a closed position over the intake end of the duct. The other end of the duct 5 is curved upwardly from the by-pass pipe 3 and communicates with the interior of a casing 7 through the side thereof. The top wall of the upwardly disposed portion of the duct 5 describes a compound curve as at 8 and the said curved upper wall is provided with a door 9 which normally remains in a closed position over its door opening in the wall. A hopper depends from the bottom or lower portion of the casing 7 and end portions of the hopper are disposed at the opposite sides of the by-pass pipe 3 and their lower ends are closed by slideable panels 11 which may be removed from the hopper when it is being emptied of its contents.

A duct 12 communicates with the interior of the casing 7 at the top thereof and at the side thereof opposite that side at which the duct 5 connects with the casing. From the casing 7 the duct 12 is downwardly curved and communicates with the interior of the by-pass pipe 3 through the top side thereof and at a point adjacent the valve mechanism 4.

A screen drum 13 is journaled for rotation in the casing 7 and is disposed transversely across the inner ends of the ducts 5 and 12 and above the upper ends of the hopper 10. The curved wall 8 of the duct 5 gradually approaches the periphery of the drum 13 from the lower end of the said curved wall toward its upper end and the upper edges of the ducts 5 and 12 are spaced from the upper portion of the periphery of the drum. A flexible strip 14 bridges the space between the lower edge of the duct 5 and the periphery of the drum and a flexible strip 15 bridges the space between the lower edge of the duct 12 and the periphery of the drum. As the said drum rotates these strips flex or bend in the direction of rotation of the drum and serve to assist in removing material from the periphery of the drum and prevent the air draft from lifting trash out of the hopper and between the lower edges of the ducts and the periphery of the drum.

A cylinder hood 16 is mounted upon the top of the casing 7 and the interior of the hood communicates with the interior of the casing as best shown in Figure 1 of the drawing. A breaker 17 is journaled for rotation in the hood upon an axis which is

parallel with the axis of the drum 13. The shaft of the breaker 17 carries at one end portion a relatively small gear wheel 18 which meshes with a relatively large gear wheel 19 mounted upon the shaft of the drum 13 at a point beyond one side of the casing 7. A belt pulley 20 is mounted upon the shaft of the breaker.

When the breaker is rotated rotary movement is transmitted through the intermeshing gear wheels to the drum whereby the breaker rotates at a relatively fast rate of peripheral speed and the drum rotates at a relatively slow rate of peripheral speed and the breaker and drum rotate in opposite directions.

The lower part of the breaker during the rotation thereof moves from the end of the duct 5 toward the inner end of the duct 12 and the upper portion of the drum moves from the end of the duct 5 toward the inner end of the duct 12.

The breaker 17 is provided upon its periphery with a series of ridges 21 with furrows intervening between them. Each ridge is provided with one side or face 22 which lies in a plane disposed upon the radius of the breaker, and at its opposite side with a face 23 which lies in a plane disposed upon a tangent to an arc or circle struck from the axis of the breaker. Radially disposed and spaced pins 24 are mounted upon the peaks of the ridges. The faces or surfaces 23 are disposed upon those sides of the ridges which lie in the direction of the rotation of the breaker.

In operation the seed cotton is drawn by the suction draft through the pipe 1 and ducts 5 and 12. As the cotton approaches the screen drum it is slightly compressed or compacted by the wall 8 of the duct 5. When the cotton comes in contact with the upper portion of the drum some of the dust and loose trash passes through the openings in the periphery of the drum and falls into the hopper 10. As the cotton passes over the top of the drum it is encountered by the ridges of the breaker whereby the cotton is slightly compressed and the twigs and bolls are broken and the cotton is passed in the form of a loose stream or mat toward and into the receiving end of the duct 12. At the same time the pins 23 encounter the cotton and subject the same to a combing action and they also serve to assist in passing the cotton over the drum from one duct to the other.

While pins have been used for kicking and tearing cotton upon revolving elements it will be observed that they have no such function in the present invention, but are merely for the purpose of lifting the compacted cotton from the screen to loosen it so that it will pass freely with the suction draft of and away from the screen drum.

Therefore the cotton will not adhere to the drum and be carried by the same and cause choking.

Having described the invention, what is claimed is:

1. Cotton cleaning apparatus comprising a casing, an inlet duct communicating with the casing at one side thereof, an outlet duct communicating with the casing at the opposite side and at the top thereof, a screen drum journaled in the casing, a hood mounted upon the casing and a breaker member journaled for rotation in the hood.

2. Cotton cleaning apparatus comprising a casing, an inlet duct communicating with the casing at one side thereof, an outlet duct communicating with the casing at the opposite side and at the top thereof, a hopper located below the casing and communicating therewith, a screen drum journaled in the casing, a hood mounted upon the casing and a breaker member journaled for rotation in the hood.

3. Cotton cleaning apparatus comprising a casing having inlet and outlet ducts, a screen drum journaled for rotation in the casing, a hood mounted upon the casing and a rolling breaker member journaled for rotation in the hood, said breaker member rotating oppositely to the drum, having upon its periphery a series of ridges with intervening furrows and outstanding pins mounted upon the peaks of the ridges to loosen the cotton from the screen as it is rolled and crushed.

4. In a cotton cleaner a screen drum, means for directing a blast of air transversely through the drum, a breaker journaled above the drum, means for rotating the drum and breaker simultaneously and at different rates of speed and in opposite directions one to the other, the breaker being provided upon its periphery with a series of ridges and intervening furrows and outstanding pins mounted upon the peaks of the ridges.

5. In a cotton cleaner, a breaker journaled for rotation and having upon its periphery a series of ridges each presenting an unbroken crushing edge or peak and having outstanding pins mounted upon the peak of the ridges, whereby the cotton is rolled by the crushing ridge and the rolled cotton loosened up by the pin as it comes from under the rolling ridges.

6. In a cotton cleaner, a breaker journaled for rotation and having upon its periphery a series of crushing ridges each presenting an unbroken edge and having an inclined wall and a radial wall terminating in said edge, the inclined wall being on the side in the

direction of movement, and outstanding pins mounted upon the peaks of the ridges, whereby the cotton is pressed down by a rolling contact of the inclined wall of the ridges and the rolled cotton loosened as each ridge passes thereover.

7. A cotton cleaner apparatus comprising a pneumatic conveyer duct, a casing forming an inlet element thereof, a screen drum journaled in the casing and rotating to advance the cotton therein, and a breaker roll arranged in close proximity to said drum and adapted to rotate opposite to the direction of rotation of the drum and carrying upon its periphery breaker faces arranged transversely to the path of the cotton in oblique relation thereto and extending upwardly and forwardly in the direction of their movement within the path of the cotton, whereby the bolls and hulls are opened up by successive crushings and rollings between the breaker surfaces and the drum.

8. A cotton cleaner apparatus comprising a pneumatic conveyer duct, a casing forming an inlet element thereof, said ridges having each an unbroken crushing edge and a screen drum journaled in the casing and rotating to advance the cotton therein, and a breaker roll arranged in close proximity to said drum and adapted to rotate opposite to the direction of rotation of the drum and carrying upon its periphery breaker ridges having each a rearwardly facing radial wall and a forwardly facing wall, said latter wall being inclined forwardly and inwardly from the radial wall whereby to form pockets for the cotton and cause the cotton bolls and hulls to be subjected to the successive rolling and crushing actions of the inclined walls of the breaker roll.

9. In a cotton cleaner, a breaker journaled for rotation and provided upon its periphery with a series of ridges with intervening furrows, said ridges having each an unbroken crushing edge and the opposite side walls of the ridges diverging from each other from the peaks of the ridges at different angles.

10. A cotton cleaning apparatus comprising a casing, an inlet duct communicating with the casing at one side thereof, an outlet duct communicating with the casing at the opposite side and at the top thereof, a screen drum journaled in the casing and forming at the inlet duct a converging space between the surface of the drum and the casing wall, a hood mounted upon the casing, and a breaker member journaled for rotation in the hood.

In testimony whereof I affix my signature.
CHARLES ROBERT WOOD.
